UNITED STATES PATENT OFFICE

CARBON P. DUBBS, OF WILMETTE, ILLINOIS, ASSIGNOR TO UNIVERSAL OIL PRODUCTS COMPANY, OF CHICAGO, ILLINOIS, A CORPORATION OF SOUTH DAKOTA

PROCESS FOR CONVERTING HYDROCARBONS

Application filed July 24, 1918. Serial No. 246,438.

This invention relates to improvements in process for converting hydrocarbons and refers more particularly to a process of converting heavy into lighter hydrocarbons such 5 as gasoline-like products.

Among the salient objects of the invention are to provide a process in which the oil is compelled to pass through a plurality of relatively small streams in the fire or crack-10 ing zone and then through a larger chamber or chambers located outside of the fire zone and forming the vapor or distilling zone; to provide a process in which the oil is circulated rapidly through the fire zone and relative-15 ly slowly through the vaporizing zone; to provide a process in which the oil is circulated through the fire zone in streams of progressively decreasing size to insure the highest economy of operation and most efficient 20 cracking; to provide a process which permits of the use of relatively small pipes in the fire zone and in which the deposition of carbon is substantially eliminated in that 25 part of the apparatus which is subjected to the highest heat; to provide a process in which the precipitated carbon is deposited in that part of the apparatus located outside of the fire zone; to provide a process in which a 30 regulated quantity of oil is at all times automatically supplied to the system to prevent the pipes becoming dry; to provide a process in which the cracking, distilling and condensing can take place under the pressure of the 35 generated vapors; to provide a novel form of apparatus for carrying out the above process and in general to provide novel improvements of the character referred to.

In the drawings—

Fig. 1 is a side elevation of the apparatus 40 with parts shown in dotted lines.

Fig. 2 is a view partly in plan and partly in horizontal section.

Fig. 3 is a transverse cross sectional view.

Fig. 4 is an end elevation of the apparatus, 45 partly in section.

Referring to the drawings, 1 designates the furnace, in the fire zone of which is mounted a plurality of sets of relatively small pipes, 2, 3, 4 and 5 respectively. The first sets 2, may 50 be 1 1/4 inches in diameter; the set 3, an inch

in diameter; the set 4, three-fourths inches in diameter and the set 5, one half inch in diameter. The exact diameter of each set may of course vary with conditions of operation but should be of the correct size relative to the desired speed, friction, amount of vapors taken off, character of product desired, etc. 55

These pipes are connected in series and the oil is delivered to them by means of a pump 6 through pipe 12a. Mounted above the cracking coils and located outside of the fire zone are four vapor chambers 7, 8, 9, and 10 respectively, there being a vapor chamber for each of the cracking coils. These vapor chambers may take the form of ten 60 inch pipes and are inclined somewhat downwardly toward the end of the apparatus at which the pump is located. The vapor chambers are connected at one end to the respective coils by pipes 11 and at their other ends to the adjacent set of coils by pipes 12. Each vapor chamber at one end is connected to a vertical aerial condenser 13, the connections to the aerials being controlled by valves 14. The aerials are connected to the inclined pipes 15 leading to manifold 16 which in 65 turn is connected by pipe 17 to the water condenser coil 18. The condenser 18 leads to receiving tank 19 having draw-off 20 which is controlled by valve 21. Valves 22 are interposed in the inclined pipes 15 so that pressure can be regulated on the system as desired. A baffle 23 may be interposed, if desired, in the vapor chambers which are also provided with gauges 24 and 25. The coils are at all times filled with oil but of course 70 the vapor chambers will not be. To prevent the system going dry by excess vaporization or otherwise, I provide means for automatically supplying additional oil to the system. This means for supplying additional oil to the system comprises a tank 26 connected by a line 27, having interposed 75 therein a valve 28, to a header 28b. From this header three lines 28a communicate respectively with the lines 12' and 12 leading to the inlets of coils 3, 4 and 5, which coils discharge into expansion chambers 8, 9 and 10, respectively. It will be seen therefore 80 that an open communication is used between 100

the tank 26 and the expansion chambers 8, 9 and 10. The tank 26 has communicating therewith an oil inlet line and is provided with a float valve 29. The arrangement of this float valve is such that whenever the oil in any one of the chambers 8, 9 and 10 falls below a predetermined level, oil will be introduced to the tank and passed directly therefrom to the chamber to again establish the desired liquid level therein. The vapor pressure in the tank 26 is maintained equal to the pressure in the chambers 8, 9 and 10 by the provision of a communication 30 between the receiving tank 19 and the tank 26, which communication permits the pressure to be equalized in the expansion chambers, the receiving tank 19 and the tank 26.

The temperature and pressure to which the oil is subjected will vary with conditions, both with the character of the oil treated with the desired gravity or endpoint to be obtained as well as other conditions. The pressure may vary from 50 to several hundred pounds although in some cases the process may be operated at less than 50 pounds pressure, as for example 20 to 30 pounds. The temperature of the oil in the small tubes will vary from about 400° F., more or less, to 1200° F., more or less. The following illustrative run may be given. Starting with gas oil from the Kansas or Oklahoma fields of 32 degrees Baumé gravity,—the oil after being raised to a cracking temperature in the heating tubes, while maintaining the system under a substantial pressure, a yield of from 30-60% of the original charge of 400 degrees end point gasoline of from 56-58 degrees Baumé gravity may be produced.

The residue is drawn out of the last vapor chamber through pipe 31 which is connected by pipe 32 to a fractionating still 33. This still 33 is connected with gooseneck 34, water condenser 35 and receiving tank 36. A pipe 36' provided with valve 36'' leads from the receiver 36 to the pipe leading to the inlet side of the pump 6. The pipe 32 is provided with a valve 37 set at a pressure under which the system is operated. In the pipe 32 is interposed a tank 38 and in this tank 38 is interposed a float 39 which regulates the rate of flow of the oil from the last vapor chamber through and out of the tank 38, irrespective of the pressure. The upper end 55 of this chamber 38 is provided with a gas inlet pipe 40 which is opened to the incondensable gases in the receiving tank 19. The arrangement is such that when the level in the last vapor chamber exceeds the normal amount, the float valve 39 will rise and permit the excess residue to pass into the receiving tank 38 and thence continuously from this tank on to the atmospheric still 33, the pressure on the hot residual oil being 65 released by the pressure valve 37, it being ap-

parent that the still 33 is under atmospheric pressure. The construction in tank 38 is similar to that shown in tank 26. The residue which goes into the fractionating still is there fractionally distilled and the distillates which go over into the condenser are again returned to the cracking system for retreatment. The residue which is left in the fractionating still will contain most of the precipitated carbon.

The arrangement is such that the oil passes through the vapor chambers to the next adjacent coil by gravity assisted by the pump. By this means a sufficient rapid circulation of the oil through the cracking coils to the vapor chambers is obtained.

I claim as my invention:

1. A continuous process for cracking hydrocarbon oils, consisting in continuously passing a stream of oil from a primary source of supply through a heating zone wherein it is subjected to a cracking temperature, in passing the highly heated oil from said stream to an enlarged reaction zone wherein conversion occurs, in maintaining a predetermined liquid level of the oil in said enlarged reaction zone by automatically supplying additional oil from an auxiliary source of supply to said stream when the liquid in the reaction zone falls below said predetermined level, and in maintaining a superatmospheric pressure on the oil undergoing conversion.

2. A process for converting hydrocarbon oil, consisting in heating a stream of oil from a primary source of supply to a cracking temperature while passing through an elongated passageway, in delivering the highly heated oil from said passageway to an enlarged reaction zone wherein conversion occurs, in maintaining a predetermined liquid level of the oil in said enlarged reaction zone by automatically admitting additional oil from an auxiliary supply to the inlet of said elongated passageway, when the oil in the enlarged reaction zone falls below said predetermined level and in maintaining an equalized pressure on the oil in said enlarged reaction zone and in said auxiliary supply.

3. A process for cracking hydrocarbon oil, consisting in passing a stream of oil from a source of supply through a heating zone wherein it is raised to a conversion temperature, in delivering the highly heated oil from said stream to an enlarged reaction zone, wherein conversion occurs, in passing unvaporized oil from said enlarged reaction zone through a second stream wherein it is again subjected to a conversion temperature, in discharging the heated oil from said second stream into an independent enlarged reaction zone, in maintaining predetermined liquid level of the oil in each of said enlarged reaction zones by separately and automatically admitting to said streams additional oil from

an auxiliary source of supply in the event that the oil in said enlarged reaction zones falls below said predetermined liquid levels and in maintaining a self-generated superatmospheric vapor pressure on the oil undergoing conversion.

4. A process for cracking hydrocarbon oil, consisting in maintaining a plurality of independent bodies of hydrocarbon oil under cracking conditions of heat and pressure, in continuously supplying hydrocarbon oil from a primary source of supply to said bodies and in maintaining the volume of the oil in each of said bodies substantially constant by automatically admitting to said bodies additional oil from an auxiliary source of supply in the event that the volume of oil in said bodies decreases.

10 5. A process for cracking hydrocarbon oil, consisting in continuously passing a stream of oil from a primary source of supply through a heating zone, wherein the oil is raised to a cracking temperature, in delivering the oil, subsequent to its being raised to a cracking temperature in said stream, to an enlarged zone, wherein substantial vaporization occurs, in maintaining a predetermined volume of liquid oil, undergoing treatment in the process by automatically supplying additional oil to said stream from an auxiliary source of supply, when said volume of oil falls below the predetermined volume desired to be maintained in the process, and in maintaining a superatmospheric pressure upon the oil undergoing cracking in the process.

20 6. A continuous process for cracking hydrocarbon oils, consisting in continuously passing a stream of oil from a primary source of supply through a heating zone, wherein it is subjected to a cracking temperature, in delivering the oil, subsequent to its passage through said heating zone, to an enlarged zone, wherein substantial vaporization occurs, in maintaining a predetermined volume of liquid oil in said enlarged zone by automatically supplying additional oil from an auxiliary source of supply to said stream, when the volume of oil in said enlarged zone falls below the predetermined volume desired to be maintained therein, and further by automatically removing any excess of liquid accumulating in said enlarged zone, and in maintaining a superatmospheric pressure on the oil undergoing conversion.

25 7. A process for cracking hydrocarbon oil, consisting in maintaining a predetermined volume of liquid oil in a still under cracking conditions of temperature and pressure, in normally supplying the oil to said still from a source of supply in maintaining an auxiliary supply of liquid oil under the same pressure as is maintained upon the oil in the still and in automatically admitting oil from such auxiliary supply to the still, in the event 30 of a decrease in the predetermined volume of

oil desired to be maintained therein, in maintaining a body of unvaporized residual oil, withdrawn from said still, under the same pressure as is maintained upon the oil in the still, and in discharging unvaporized residual oil from the still to said body, when the volume of oil in the still exceeds the predetermined volume desired to be maintained therein.
